UNITED STATES PATENT OFFICE.

CHARLES WAINWRIGHT, OF ERIE, PENNSYLVANIA.

PLATE-VALVE.

1,334,198.

Specification of Letters Patent. Patented Mar. 16, 1920.

Application filed June 21, 1918. Serial No. 241,272.

To all whom it may concern:

Be it known that I, CHARLES WAINWRIGHT, a citizen of the United States, residing at Erie, in the county of Erie and State of Pennsylvania, have invented new and useful Improvements in Plate-Valves, of which the following is a specification.

My present invention pertains to plate valves.

- 10 It is essential in plate valves that the velocity of flow of gases be kept low through eduction ports controlled by plates and this notwithstanding the flow through induction ports may be of considerably higher velocity. High velocity through discharge valves is objectionable because it imposes too much strain on the valves; and it is a desideratum or ideal to so construct a valve that no back-stop is needed.
- 20 The general object of my present invention, therefore, is the provision of a valve construction possessed of practically unlimited elasticity—*i. e.*, a construction that assures the desired low velocity through eduction ports and thereby obviates the necessity of employing back stops.

To the attainment of the foregoing the present invention consists in the built up construction of valve with all plates extending in the same direction except those at the end of the box plate valve when the same is used as an inlet valve for a compressing apparatus, as hereinafter described and definitely claimed.

35 In the accompanying drawings which are hereby made a part hereof:

Figure 1 is a vertical section showing one type of valve constructed in accordance with my present invention.

40 Fig. 2 is a plan view of one of the resilient plates, removed.

Fig. 3 is a view similar to Fig. 1 showing another type of valve embodying my invention.

45 Referring by numeral to the said drawings and more particularly to Figs. 1 and 2 thereof, 1 is a portion of apparatus, having an eduction port 2, and 3 is the cage of my novel valve construction. The said cage 50 3 is disposed in registration with the port, and in superimposed relation upon the wall about the port, and is provided with a horizontal lower series of vertically elongated ports 4, and is also provided with an upwardly extended portion 5 in which are

ports 6 in the form of notches, as illustrated. These ports 6 are in communication with ports 7 arranged in an upper horizontal series; the said ports 7 being formed between upright portions 8 of the cage which 60 portions 8 serve to join the annular portion of the cage in which the ports 4 are formed with the interior member 9 of inverted truncated cone shape; the said member 9 extending downwardly within the said annular 65 portion and being provided with an open-work top 10, as illustrated.

Grouped about the annular cage portion in which the ports 4 are formed are the resilient plates 11 comprised in the lower 70 series of plates; there being one plate to each port 4, and each plate being connected to the annular cage portion at its lower end by a screw 12 or other suitable means and normally bearing at its upper end against 75 the outer side of the annular portion above its respective port. At 13 are the plates of the upper horizontal series. These plates 13 control the ports 6, and there is one plate 13 to each port 6, and each plate 13 is connected by a screw 14 or other suitable means 80 below its respective port and normally bears at its upper end against the portion of the cage above the port as illustrated.

At 15 is a closure in which bears a threaded 85 bolt 16, equipped with a lock nut 17 and impinging at its lower end against the upper end 10 of the cage. It will be manifest from the foregoing that a plate valve characterized as described is possessed of practically 90 unlimited elasticity, and permits of such low velocity through eduction ports that the employment of back stops is rendered unnecessary.

In the embodiment shown in Fig. 3 the 95 cage is shown as superimposed upon an open-work frame 18 and having a lower cross bar 19 joined by a screw 20 to the upper end of the frame. The said cage is provided with a lower series of ports 21, an upper series of 100 ports 22, a lower series of plates 23 complementary to the ports 21 and an upper series of plates 24 complementary to the ports 22, all of the said plates being arranged externally of and individually connected to the 105 cage as shown. It will also be noted by reference to Fig. 3 that the cage is provided with an upper wall 25, having vertically disposed ports 26 each of which is controlled by a plate 27 individually secured to the top of 110

the cage. In this embodiment of the invention the plates 27 are adapted to serve as inlet valves for a compressor.

Having described my invention what I claim and desire to secure by Letters-Patent is:

1. In a plate valve, the combination of an annular cage with an induction port at one end and a plurality of exterior valve seats 10 and ports extending therefrom to the interior of the cage and arranged one port to one valve seat, and a series of flexible plates surrounding the cage and each connected at one end thereto, and arranged one plate to each valve seat and the port complementary thereto, the total net area of the said ports exceeding the area of the induction port.
2. In a plate valve, the combination of an annular cage with an induction port at one end and a plurality of sets of exterior valve seats and ports extending therefrom to the interior of the cage and arranged one port to one valve seat and sets of flexible plates 25 surrounding the cage and each connected at one end thereto and arranged one plate to each valve seat and the port complementary thereto, the total net area of the said

ports exceeding the area of the induction port.

3. In a plate valve the combination of the cage having a series of ports in its side wall and also having ports in one end wall, a set of plates arranged exteriorly of the side wall of the cage and each opposite one of the ports in said side wall and connected adjacent to one end to said side wall, and plates opposed to and each connected adjacent to one end to the end wall of the cage and each arranged opposite one of the ports in said end wall.

4. In a plate valve, the combination of a cage having a plurality of sets of ports in its side wall and also having an induction port at one end and a plurality of ports in its opposite end, sets of flexible plates arranged exteriorly of the side wall of the cage and arranged one plate to one port and the seat complementary to the port, and flexible plates opposed to and each connected adjacent to one end to the last-named end of the cage and each arranged opposite one of the ports in said wall to control said port alone.

In testimony whereof I affix my signature.

CHARLES WAINWRIGHT.
